UNITED STATES PATENT OFFICE.

WERNER MEIER, OF ZURICH, SWITZERLAND, ASSIGNOR, BY MESNE ASSIGNMENTS, TO FIRMA AKTIENGESELLSCHAFT J. ZEHNDER & SOHNE, OF GRANICHEN, SWITZERLAND.

MEANS FOR ELECTROMAGNETICALLY FIXING WORK PIECES.

Application filed April 9, 1920. Serial No. 372,441.

To all whom it may concern:

Be it known that I, WERNER MEIER, a citizen of the Republic of Switzerland, residing at Zurich, Bolleystrasse 40, Switzerland, have invented certain new and useful Improvements in Means for Electromagnetically Fixing Work Pieces, and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to means for electromagnetically holding work pieces. The electromagnetic plates or chucks used heretofore for holding work pieces for instance in grinding machines, are worked with direct current. As a rule alternating current is used in work shops for lighting and driving purposes, therefore the use of a direct current magnet plate necessitates either a direct current generator or a converting of alternating current into direct current, for instance by means of a rotary convertor. The use of electromagnets excited by alternating current would bring the important advantage of enabling the utilization of alternating current directly for magnetizing without having to transform it first into direct current.

The object of the present invention is an electromagnetically operated chuck wherein at least two magnets magnetized by alternating current are used beside each other.

In using alternating current directly for magnetizing purposes to generate large pulling forces the following difficulties present themselves:

a. A vibration of the work piece takes place caused by the pulsations of the current;

b. The pulling force is not constant;

c. A heating up of the work piece to be held takes place originating from the hysteresis from eddy-currents and short circuit currents.

Fig. 1 of the accompanying drawings illustrates by way of a diagram the pulling force of an alternating current magnet in which i is the instantaneous value of the alternating current, B the induction and Z the pulling force. The relation of these

values is expressed in the equations $B=c.E=c'i$ further $Z=c''B^2$ in which c , c' and c'' are constants. As the pulling force is in proportion to the square of the induction, it is always positive if the latter is not equal to zero.

It results from the foregoing that the pulling force is equal to zero at certain intervals and it is therefore possible that the piece of work can shift during these intervals. In order to do away with this principal disadvantage of the alternating current magnets, the magnetizing currents of the alternating current magnets are chosen so that a difference of phases exists between them. In consequence thereof the pulling forces of both magnets do never at the same time become equal to zero, i. e. a pulling force is always exerted by one of the magnets. This arrangement presents moreover the advantage that the vibrations disappear. The difficulties mentioned above sub a and b are overcome in this way.

In the case of single phase current two magnetic circuits with a difference of phases may be obtained in inserting into one of the circuits induction coils and in saturating the two circuits unequally.

The E. M. F. of self-induction, on which the arrangement principally depends is:

$$E_L = \frac{4\pi}{10} \cdot \frac{s^2 \cdot q}{l} \cdot \frac{dB}{dH} \cdot \frac{di}{dt} \cdot 10^{-8}, \quad 85$$

wherein s is the number of turns, q the cross-section, l the average length of the magnetic circuit, B the induction, H the intensity of field, c the instantaneous value of the current and

$$\pi = 3.1416 \cdot \frac{dB}{dH} \quad 95$$

is the tangent to the hysteretic loop. By means of a variety of saturations large differences in E_L are attained, which involve different phase angles.

In the case of two-phase or three-phase current these artificial means of causing a phase-displacement are superfluous, as the phase-currents are already out of phase by 90° or 120° resp. The variation with the time of the magnetic flux in the single magnetic circuits, when using three-phase current, is illustrated in the vector-diagram of Fig. 2. The three vectors I, II, III present

the fluxes of the out-of-phase magnetic circuits. The vectors rotate around point O, the projections of the three phases onto line N—N show the instantaneous values of the fluxes. The pulling force is proportional to the square of the fluxes. Further it may be seen from the vector-diagram that the fluxes are never equal to zero and therefore the pulling force can never be equal to zero.

10 If the magnetic cores were maximally saturated, a large work piece would be considerably heated up by the eddy- and hysteresis-currents. Preferably the cores are only slightly saturated and B has to be chosen to 3000-10000 lines, whereupon only a slight heating-up takes place. With such a small saturation large and small work pieces are attracted with the same pulling force, because the pulling force per square centimeter is small with large work pieces but the surface is large whereas with small work pieces the pulling force per square centimeter is very large, because all the lines of force of the magnet are concentrated over a small surface. Thus the same pulling force is attained as for a large work piece.

15 On the accompanying drawings the exemplifications of the invention are shown:

Fig. 3 shows one mode of carrying out the invention partly in front view, partly in vertical section.

20 Fig. 4 is a plan of Fig. 3.

Fig. 5 is a side view partly shown in section.

25 Fig. 6 shows a diagram of connections.

30 Fig. 7 is a diagrammatic sketch.

35 The cores 1, 2, 3, 4, 5, 6 of the magnet consisting of silicon dynamo sheets are connected in pairs to a yoke 7. Coils 8 are situated on the cores 1, 2, 3, 4, 5, 6 the ampere-turns of which produce the magnetic lines of force. Each magnet is screwed by means of brass screws 9 to a chuck base plate 10 of iron. A cast-iron chuck frame 11 is mounted on the baseplate, brass facings 12 are arranged between frame 11 and the magnets for the purpose of magnetic insulation. Between the free ends of every chuck magnet core bars of fibre 13 are arranged for insulating them electrically and magnetically. The magnetic circuits are closed by means of a work piece 19 shown in Fig. 3 in dotted lines, and the fibre bars 13 prevent a direct passage of the magnetic lines from one core 40 to the next. The whole apparatus is enclosed by a chuck covering 14 of aluminum. The electromagnetic chuck illustrated serves principally for holding the work in machine tools and its coils are connected up so that three phase alternating current may be used for working same. To this end the magnet coils 8 are connected to a plug device 15 with which they are electrically connected in a manner shown diagrammatically 45 in Fig. 6. The chuck cores 1, 2, 3, 4, 5, 6

form three magnetic circuits each of which is excited by one of the phases. The other half of the apparatus shown in Fig. 3 is similarly arranged as the one above described.

Every three adjacent magnets comprising six cores form together a chuck plate element, the chuck shown in Fig. 3 consists therefore of two plate elements arranged in one axis. The plate elements for alternating current might also be arranged beside each other or in a circle or in any other way to suit special requirements. Each plate element is provided with a plug device 15 as shown in Fig. 6. The plug devices are connected electrically to each other so that one part or the other or both of the holding device may be switched on as desired. Moreover the plug device is arranged so and the coils are connected up to it in such a way that it is made possible to connect the coils 8 of one set of magnet cores 1, 2, 3, 4, 5, 6 in star or delta connection. Two adjacent magnets are therefore fed with out-of-phase currents. In inserting a three-pole plug into one or the other set of holes 16 and 17 star- or delta-connection is produced. When such a plug is inserted into the upper three holes 16 the magnet coils are connected in star connection, when it is inserted into the holes 17 the coils are in delta connection. The plug devices are connected electrically with the plug holes 18 adapted to be connected to a power main. The pulling force varies in accordance with the connection made as: $Z = c'' \cdot B^2 = c''' \cdot E^2$, the pulling forces are theoretically in a ratio of 1:3.

In contradistinction to a device for holding work pieces electromagnetically by means of direct current in which the magnet cores are insulated magnetically from each other by means of zinc bars, these zinc bars cannot be used with alternating current as short circuit-currents would be generated therein, they would act as short-circuited windings of a transformer as shown in Fig. 7. These short circuit currents would generate much heat and the device would become too hot.

The path of the magnetic lines is indicated in Fig. 3. The lines which do not close within the work piece are stray lines and they may be taken to be 5% of the total magnetic flux. In the drawing the pole-shoes are of an elongated shape whereby the phases are arranged nearer to each other.

The device for fixing work pieces may consist of three, six, nine etc. magnetic circuits to suit the size of work pieces.

It is not absolutely necessary that the magnetizing currents for the various magnet coils differ in phase, for small pulling forces the phases may also coincide.

I claim:

An alternating current electro-magnetic

chuck comprising an oblong chuck base plate, a frame extending around the edges of said plate, a metallic magnetic insulator seated in said frame, narrow, spaced, 5 laminated magnetic cores mounted on said insulator, said cores arranged transversely of the longitudinal axis of said plate and frame, screws passing through said plate and engaging said cores to hold them on 10 said insulator, a solid insulating material filling the spaces between the outer ends of

said cores and forming with the outer ends of the cores a plane chucking face, windings on said cores for alternating current, means to differently connect the windings to change the holding power of the chucking face, and a casing between said base plate and chucking face, said base plate, casing and chucking face connected water-tight. 15

In testimony that I claim the foregoing as my invention, I have signed my name.

WERNER MEIER.
